UNITED STATES PATENT OFFICE.

JAMES EDWARD CHAMBERS, OF MEMPHIS, TENNESSEE, ASSIGNOR OF ONE-HALF TO
C. W. WALLIS, OF MOORHEAD, MISSISSIPPI.

WINDOW-SHADE SUPPORT AND SHIELD.

1,201,697.

Specification of Letters Patent. Patented Oct. 17, 1916.

Application filed March 22, 1916. Serial No. 85,982.

To all whom it may concern:

Be it known that I, JAMES E. CHAMBERS, a citizen of the United States, residing at Memphis, in the county of Shelby and State 5 of Tennessee, have invented certain new and useful Improvements in Window-Shade Supports and Shields; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in window shade supports and shields and it has for its object to provide a support which may be quickly adjusted to windows of different widths and the telescoping support being held in adjusted position by pins in the ends of the curtain rollers.

A further object of the invention is to 25 provide curtain supports comprising telescoping shield members having end bracket members adapted to be secured to the inside of the window frame or to the face thereof, said support being so constructed as to carry 30 twin shades.

The invention comprises various details of construction, combinations and arrangements of parts, all as will be more fully hereinafter described, shown in the accompanying drawings and then specifically defined in the appended claim.

My invention is illustrated in the accompanying drawings, in which:

Figure 1 is an elevation showing the support secured to the face of a window frame. 40 Fig. 2 is a similar view showing the support fastened to the inside of a window frame. Fig. 3 is an enlarged detail view of a portion

of the support. Fig. 4 is an end view of the same, and Fig. 5 is a detail sectional view 45 taken on line 5—5 of Fig. 1.

Reference now being had to the details of the drawings by letter, A designates a window frame and A' A' represent the telescoping members of the shade support, said 50 members having extensions A² which are slotted as at A³ to receive suitable securing nails or screws A⁴, as shown in Fig. 1 of the drawings, and in Fig. 2 the extensions A² are bent inward as indicated by dotted lines and secured to the inner side of the frame. The extensions A² are bent back upon themselves as at A⁵ (Fig. 5) and are held by lugs A⁶ 55 flat against themselves to the point A⁶ where they are bent at right angles to form flanges 60 A⁷ and are provided with suitable openings A⁸ to receive the gudgeons B of the shade rollers B'. Said gudgeons are provided with holes to receive pins or split keys B² which serve to secure the gudgeons in place 65 and also to hold the telescoping shield members in adjusted position relative to each other.

What I claim to be new is:—

A shade support comprising a shield provided at its ends with extensions which are folded back upon themselves, said extensions being provided with slots and terminating in inwardly disposed flanges located between the ends of the shield and which are provided with openings for the reception of gudgeons of shade rollers, one fold of each extension being provided with lugs which overlap the edges of the other fold of the same extension. 75

In testimony whereof I hereunto affix my signature in presence of two witnesses.

JAMES EDWARD CHAMBERS.

Witnesses:

JAMES H. GODSEY,
J. Q. COPPAGE.
